UNITED STATES PATENT OFFICE.

JAN WOLSKI, OF CHICAGO, ILLINOIS.

TRIP-OPERATED RAILWAY-SWITCH.

1,122,562.

Specification of Letters Patent. Patented Dec. 29, 1914.

Application filed September 18, 1914. Serial No. 862,304.

To all whom it may concern:

Be it known that I, JAN WOLSKI, a subject of the Czar of Russia, residing at Chicago, in the county of Cook and State of Illinois, have invented certain new and useful Improvements in Trip-Operated Railway-Switches, of which the following is a specification.

This invention relates to new and useful improvements in trip operated railway switch.

The primary object of the invention is to provide a shiftable switch tongue adapted to be actuated from an approaching car and then returned to its normal position after the car has passed the switch tongue.

A further object of the device is to provide a normally closed siding switch adapted to be closed by an approaching car for allowing its passage upon the main track and further providing for a return of the siding switch to its opened position after the car has passed the same.

A still further object is to provide a railway switch actuator especially adapted for street railways and arranged for manipulation by an approaching and a receding car by the proper positioning of a foot lever upon the moving car.

With these general objects in view and others that will appear as the nature of the invention is better understood, the same consists in the novel combination and arrangement of parts to be hereinafter fully described, illustrated in the accompanying drawings and pointed out in the appended claim.

In the drawings forming a part of this application and in which like designating characters refer to corresponding parts throughout the several views: Figure 1 is a top plan view of a portion of a railway with the present invention installed thereon but with the covers for the mechanism casings removed. Fig. 2 is a vertical central longitudinal sectional view thereof taken upon the central line of the main track. Fig. 3 is a central vertical transverse sectional view taken through the casing of the setting mechanism. Fig. 4 is a similar view taken through the casing of the switch

throwing mechanism. Fig. 5 is a similar view taken through the casing of the switch releasing mechanism. Fig. 6 is a view similar to Fig. 4 but illustrating the switch tongue in its open position. Fig. 7 is an enlarged perspective view partially broken away of the setting device. Fig. 8 is a similar view of the switch throwing device. Fig. 9 is an enlarged detail perspective view of a corner portion of the releasing device, and Fig. 10 is an enlarged perspective view of the latching means of the switch throwing device.

Referring more in detail to the drawings, it will be noted that there is herein illustrated a main track 10 and a siding or switch track 11 and that the position of the shiftable switch tongue 12 determines the passage of the car or train moving in the direction indicated by the arrow in Fig. 1 either continuously over the main track or laterally over the switch track. The switch tongue 12 being pivoted as at 13 is normally open to allow the car to pass to the switch track from the main track as illustrated in Fig. 1 and the invention broadly contemplates the positioning of setting mechanism within the casing 14 which is centrally positioned between the rails of the main track and whereby the switch throwing mechanism in a similar casing 15 is actuated to open the switch tongue and position the same as illustrated in Fig. 6 to allow the car to continue its passage upon the main track. The invention also provides a releasing mechanism within another casing 16 whereby the switch throwing mechanism is released upon a passing of the car thereover and returns to its normal open position as illustrated in Fig. 4.

The switch throwing mechanism is in the casing 15 which is intermediately positioned between the casings 14 and 16 and provides a pivoted post 17 therein, which is vertically positioned and provided with a short arm 18 pivotally connected by a link 19 with a shifting block 20, which block is rigidly attached by means of a vertical pin 21 with the tongue 12 positioned thereabove. The post 17 is also provided with a long arm 22 which has an actuating rod 23 pivoted to

its free end and extending through a pipe or conduit 38 positioned beneath the road bed between the casing 15 and the casing 14, which latter casing is entered by the said rod 23. A rocking shaft 24 is horizontally journaled within the casing 14 and is provided with a short arm 25 having its upper free end pivotally connected to the end of the rod 23 which is within the casing 14. 5 The post 17 and arms 18 and 22 will be unitarily called a rocking lever, and as before stated, this rocking lever is connected by the rod 23 to the arm 25 on the rocking shaft 24. A trip block 26 projects through an opening 27 in the removable cover 28 of the casing 14 and has its bottom projection 29 pivoted to an arm 30, which arm is pivoted at substantially its center to a bracket 31 upon the bottom 32 of the said casing while 10 a long arm 33 of the rocking shaft 24 freely rests upon the free end of the arm 30. By this arrangement it will be seen that a train or a car upon the main track moving in a direction indicated by the arrow, a portion 15 of the floor 34 of such a car being indicated in Fig. 2, may be readily provided with a means for depressing the block 26 and thus shifting the tongue 12 to its closed position. Such a means is herein illustrated in the 20 form of a foot pedal 35 upon a spring pressed normally elevated vertically positioned trip rod 36, which rod is provided at its lower end with a roller 37 and being normally positioned so as to freely pass 25 above the block 26 may be readily depressed by the foot of the motorman upon the car for bringing the same in contact with the block 26 so as to depress the said block when the car is either moving or standing still. 30 By depressing the block 26 the arm 30 is actuated and thereby turns the rocking shaft 24 and moves the rod 23 for exerting a pull upon the long arm 22 of the post 17 and also pulling the link 19 by means of 35 the arm 18 which moves the block 20 inwardly and shifts the tongue 12 to its closed position as shown in Fig. 6. A lever 39 is pivoted within the casing 15 and provided with an upturned end flange 40 adapted to 40 engage over the block 20 and retain the same with the switch tongue in its closed position as shown in Fig. 10, it being noted that a leaf spring 41 holds the lever 39 resiliently in a normally elevated position, while an 45 expansion spring 42 having one end abutting a lug 43 within the casing 15 has its opposite end forcibly engaging the inner face of the block 20 and normally holds the block in its outer position and with the switch 50 tongue open.

The releasing mechanism provided in the casing 16 consists of a horizontally jour-

naled shaft 44 having an angularly extending arm 45 which freely rests upon the top of a rocking lever 46 pivoted to a bottom 65 bracket 47 of the said casing and having at its opposite end a vertically extending rod 48 hinged thereto while a trip block 49 is mounted upon the upper free end of the rod 48 and extends through the opening 50 of 70 the removable cover plate 51 of the said casing 16. The rod 44 has an upwardly extending arm 52 which arm is pivotally connected at its free end to an arm 53 of a journaled rod 54 within the casing 15 by 75 means of a connecting wire 55. The said wire 55 passes through the conduit 56 positioned between the casings 15 and 16. The rod 54 has an angularly extending finger 57 which is hinged as at 58 to an intermediate 80 portion of the lever 39.

With the switch tongue in its closed position and engaged by the flange of the lever 39, the depressing of the roller 37 into contact with the block 49 after the passage 85 of the car past the switch will depress the rod 48 and tilt the lever 46 for upwardly moving the arm 45 and partially rotating the rod 44 which thereby exerts a pull upon the wire 55 by means of the arm 52 and in 90 turn imparts a partial revolution to the rod 54 and moves downwardly the finger 57 for downwardly tilting the flanged end of the lever 39, so that the block 20 is released from the flange 40 and the spring 42 returns the block with the switch tongue to its 95 normal open position. A leaf spring 59 carried within the casing 16 bears against the arm 52 and normally holds the arm 45 against the lever 46 and with the block 49 100 normally elevated. The casing 15 being provided with a removable cover 60 has a slot 61 therethrough for the sliding reception of the switch tongue pin 21.

By this detailed description of the complete invention, the operation thereof will be apparent and the manner by which a person upon the car may throw the switch to its closed position when approaching the same and may release the switch for returning it to its open position after having passed the switch. It will also be seen that a train approaching the switch may take either the direct track or the switch track. 105

While the forms of the invention herein 110 illustrated are the preferred embodiments thereof, it will be understood that minor changes may be made without departing from the spirit and scope of the appended claim.

What I claim as new is—

A device of the class described comprising a normally open switch tongue, a spring pressed block attached to said tongue, a

rocking lever linked to said block, a rock shaft, an arm upon said shaft, a connecting rod between said arm and rocking lever, a trip block operatively connected to said rock shaft and adapted upon depression for shifting said tongue to its closed position, a flanged lever adapted for engaging said tongue in its closed position, means for releasing the engagement of the said flanged

lever and a trip block operatively connected 10 to said releasing means.

In testimony whereof I affix my signature in presence of two witnesses.

JAN WOLSKI.
